[57] CLAIM

The ornamental design for a removable hanging basket cover, as shown and described.

DESCRIPTION

FIG. 1 is a top view of a removable hanging basket cover according to the invention;

FIG. 2 is an underside perspective view thereof;

FIG. 3 is a top and side perspective view thereof, the rear and opposite side perspective view being identical; and,

FIG. 4 is a top perspective view thereof, showing the removable hanging basket cover in position of use, fitted to a conventional wire hanging basket, which is shown in broken lines for purposes of illustration only and forming no part of the claimed design.
